UNITED STATES PATENT OFFICE.

HARDINGE GOULBOURN GIFFARD, OF LONDON, ENGLAND.

INTERNAL-COMBUSTION ENGINE.

No. 820,712.

Specification of Letters Patent.

Patented May 15, 1906.

Application filed April 28, 1905. Serial No. 257,840½.

To all whom it may concern:

Be it known that I, HARDINGE GOULBOURN GIFFARD, (commonly called Viscount TIVERTON,) gentleman, a subject of the King of Great Britain, residing at 4 Ennismore Gardens, in the county of London, England, have invented new and useful Improvements Relating to Internal-Combustion Engines, of which the following is a specification.

This invention relates to internal-combustion engines working with gas or vaporized oil or spirit; and it has for its object improvements whereby explosions of greater intensity may be advantageously obtained. Hitherto it has been usual to mix air with the fuel (gas or vaporized hydrocarbon) in order to make the explosive mixture, and as nearly eighty per cent. of the air is nitrogen an excessive amount of air must be used in order to introduce a sufficient quantity of oxygen for complete combustion of the fuel. The result of this is that even with compression the combustible mixture can never become very much concentrated before it is ignited.

According to the present invention, means are provided whereby pure or nearly pure oxygen may be supplied to the engine in place of air. Tubes or other receptacles for barium oxid are employed, placed so that they can be heated to any required extent. They may, for instance, be placed in or around the exhaust-silencer or the exhaust-box. Two pumps are provided, one for forcing air under pressure and the other for exhausting the tubes after the barium oxid therein has been oxidized. Two or more sets of barium-oxid receptacles should be employed, with means whereby they may be alternately and successively connected to and disconnected from the air-forcing apparatus and the exhausting-pump, which supplies oxygen to the engine.

In use air is pumped alternately or successively through the barium-oxid receptacles under such conditions of pressure and temperature that the monoxid absorbs oxygen and becomes peroxid. For supplying oxygen to the engine the temperature or pressure conditions, or both, are so changed that the peroxid gives up oxygen and becomes reconverted to monoxid, the liberated oxygen being drawn into the carbureters for making the combustible mixture. A richer mixture

can thus be made, which, if compressed even to a less degree than has been usual hitherto for the explosive mixtures for internal-combustion engines, will contain more combustible matter in proportion to its mass or volume than can ordinarily be obtained, with the result that a more intense explosion will take place, greater heat will be developed, and greater relative expansion may be allowed to take place with the production of useful work.

In the accompanying drawing an illustration is given of a four-cylinder engine connected with apparatus for the production and supply of oxygen. The engine and other parts of the apparatus are not illustrated in detail, as the drawing is intended as a diagram only. The details of construction of such apparatus and the exact proportions of the parts thereof can be worked out by an engineer of ordinary ability from known data.

The cylinders of the engine (seen in plan) are designated by the letter *a*, the carbureters by *b*, and the exhaust-valves by *c*. A pipe *d* leads from the exhaust-valves to a casing *e*, wherein are arranged tubes *f*, containing barium oxid. The tubes are illustrated as bent or coiled in order to bring a sufficient length of tubing within reasonable compass, and deflectors or baffles *g* are shown fixed in staggered relation one to another in the casing *e* in order to cause the exhaust-gases to pass well over the tubes *f* and to heat the same in an efficient manner. In practice it will be preferable that the two tubes should be arranged as close to one another as is conveniently possible, because in the oxidizing and reducing actions which take place the amount of heat evolved in one tube tends to be equal to the heat absorbed in the other. Outlet-openings *h* at the end of the casing *e* serve for permitting the escape of the gases. A four-way cock *i* has two of its passages connected to the two tubes *f*, a third passage is connected by a pipe *k* to an air-pump *l*, while the fourth is connected through a small pressure-equalizing chamber *m* to an exhausting or suction pump *o*. The pump *o* discharges into a storage-chamber *n*, from which a pipe *p* leads to the carbureters *b*.

At the ends of the tubes *f* remote from the cock *i* are arranged small spring-held escape-valves *q*, which will allow air or gas to escape from said tubes after a pressure has

been attained therein sufficient under the conditions of temperature to cause the barium monoxid in the tubes to take up oxygen from the air and to become converted to peroxid. 5 *r* is a chamber containing soda-lime or other materials capable of removing carbonic-acid gas and moisture from air, said chamber being connected with the pump *l* through a non-return valve *s*. The carbureters *b* have inlet-valves *t* opening into the air. The barium oxid may be inserted in the tubes *f* in any suitable way, but preferably in the form of powder or small grains not completely filling the tubes.

15 The operation of this device takes place substantially in the manner above indicated. Air freed from moisture and carbonic acid in the chamber *r* reaches the pump *l* and is forced under pressure into one or other of the 20 tubes *f* through the cock *i*, and as said tube is heated by the exhaust-gases passing over it the barium oxid contained therein absorbs oxygen and becomes converted to a greater or less extent into barium peroxid. Mean- 25 while the other tube *f*, wherein the barium oxid has already been oxidized, is in communication with the exhausting-pump *o*, which so reduces the pressure in said tube that the peroxid again gives up its oxygen, 30 this latter being fed by the pump *o* to storage-chamber *n* and thence to the carbureters *b*. The cock *i* is turned at suitable intervals of time to connect the tubes alternately with the air-supplying and the exhausting appa- 35 ratus, respectively. Many different forms of mechanical contrivances well known in other types of machinery might be used for effecting the turning of the cock; but it is preferable that the device should be one actuated 40 from the shaft of the engine in order that the change from one tube to the other should be made after a certain number of strokes of the engine. The pumps *l* and *o* should also be operated directly or indirectly from the en- 45 gine-shaft. During starting of the engine and before any considerable quantity of oxygen has been generated the cylinders can take in air for making the combustible mixture through the valves *t*; but as oxygen is gener- 50 ated it will gradually replace the air until the mixture may be entirely composed of oxygen and fuel if the amount of barium oxid used is sufficient for this purpose. As the amount of oxygen supplied increases the feed of fuel 55 should also be increased by the usual means in order to make an efficient combustible mixture.

60 The casing *e*, arranged in the manner illustrated, might serve as an exhaust-silencer, and all the exhaust-gases might be passed through it. It will be understood, however, that a separate exhaust box or silencer might be employed or that a part of the gases might be allowed to escape through a silencer,

while the remainder of said gases would be 65 used for heating the barium-oxid tubes.

It must be remembered that the drawing is intended to be in large measure diagrammatic and that the apparatus could be constructed and arranged in many different 70 ways, according to circumstances. Evidently there might be several sets of tubes or receptacles for barium oxid, controlled by one or more cocks, such as *i*, and the said tubes or receptacles might contain chemical substances or materials other than barium oxid 75 capable of absorbing and delivering oxygen from air under similar conditions to those above described. Where barium oxid is used, there may be added thereto small percentages of chemical reagents capable of accelerating the evolution of oxygen by a form of catalytic action. The materials obtained by reducing nickel and cobalt oxids are believed to exert such an action. The air fed 80 to the tubes might be subjected to a preliminary heating in suitable coils, which might also be arranged in the casing *e*, and the oxygen evolved from the barium peroxid might be reheated in a similar manner before it is 85 supplied to the carbureters. Moreover, although it is one of the features of this invention that the heat of the gases of combustion, which would otherwise be wasted, should be utilized in the barium-oxid tubes, it will be 90 evident that, if desirable or convenient under certain conditions, the heat for said apparatus might be derived from other sources.

95 It is one of the objects of this invention to enable an internal-combustion engine of 100 given size to develop more power than has been possible hitherto, which will be especially advantageous in the engines of motor-vehicles or in engines applied to other uses where it is important to keep the weight as 105 small as possible consistently with good working. According to the size of the oxygen-generating apparatus used, said apparatus may supply either sufficient oxygen only to enrich the usual mixture or sufficient to 110 completely form the mixture with the combustible liquid or gas employed.

115 What I claim is—

1. The combination with an internal-combustion engine of two separate receptacles each containing a chemical substance capable of oxidation and reduction, a casing surrounding said receptacles, means for conveying the waste gases of the engine to said casing, means for supplying air to said receptacles alternately and for allowing gases to pass out from the receptacles, means for reducing the pressure in said receptacles alternately, and means for supplying evolved oxygen to the intake of the engine.

120 2. The combination with an internal-combustion engine of an apparatus containing a chemical substance which is capable of oxi- 125

dation and reduction, a casing and means for conveying the waste gases of the engine to said casing, whereby the apparatus is heated, means for supplying air intermittently to said apparatus, means for withdrawing gas from said apparatus, and means for supplying the evolved gas to the intake of the engine.

In testimony whereof I have signed my name to this specification in the presence of 10 two subscribing witnesses.
